UNITED STATES PATENT OFFICE.

JOHN P. DORAN, OF JEFFERSON, WISCONSIN.

DRIVING MECHANISM.

1,156,135.

Specification of Letters Patent. Patented Oct. 12, 1915.

Application filed November 26, 1913. Serial No. 803,093.

To all whom it may concern:

Be it known that I, JOHN P. DORAN, a citizen of the United States, and resident of Jefferson, in the county of Jefferson and State of Wisconsin, have invented new and useful Improvements in Driving Mechanism, of which the following is a description, reference being had to the accompanying drawings, which are a part of this specification.

The invention relates to driving mechanism, and more particularly to a driving mechanism for a washing machine.

It is one of the objects of the present invention to provide a washing machine having a reciprocating pounder which is also revolved during its reciprocating movement so that all of the clothes in the washing machine receptacle or tub will be uniformly acted on and thoroughly cleaned.

With the above and other objects in view the invention consists of a driving mechanism as set forth in the claims and all equivalents thereof.

In the accompanying drawings in which the same reference characters indicate the same parts in all of the views: Figure 1 is a top view of the improved washing machine, parts being broken away for clearness of illustration; Fig. 2 is a vertical sectional view thereof taken on line 2—2 of Fig. 1; Fig. 3 is a detail sectional view of the pounder portion of the machine taken on line 3—3 of Fig. 2 and on a smaller scale; Fig. 4 is a vertical sectional view taken on line 4—4 of Fig. 3; Fig. 5 is a detail view of the operating handle; Fig. 6 is a vertical sectional detail view of a modified form of pounder actuating mechanism; and Fig. 7 is a similar view of another modification thereof.

Referring to the drawings the numeral 8 indicates a tub or receptacle which may be of the ordinary or of any improved type, 45 and is provided with supporting legs 9 and a hinged cover 10. The improved washing machine actuating mechanism is mounted upon the cover and the crown or bevel gear 11 thereof has its hub portion 12 journaled 50 medially in the cover. A pinion 13 meshing with the gear 11 is mounted on a horizontal shaft 14 which is journaled in the bracket 15 carried by the cover. The outer end of the shaft 14 has fixedly mounted thereon a 55 gear wheel 16 which is in mesh with a pinion 17 journaled on a stud shaft 18 projecting

from the bracket beneath the horizontal shaft. A fly wheel 19 also journaled on the stud shaft is fixedly connected to and turns with the pinion 17 and is adapted to carry 60 the actuating parts of the mechanism over dead centers and provide easy running of the parts.

The horizontal shaft 14 is rotated by means of a hand lever 20 fulcrumed on an extension 15' of the bracket or by other means and having a link connection 21 with a wrist pin 22 projecting from the outer face of the gear wheel 16. The link is connected to the medial portion of the handle 70 and the wrist pin forms a cranked connection with the gear wheel 16 so that the oscillation of the hand lever will rotate the horizontal gear 16.

The hub 12 of the bevel gear 11 is provided with a rectangular or square bore 23 through which slidably extends the rectangular or squared portion 24 of the vertically extending pounder shaft 25. The lower end of the shaft 25 carries a pounder 26 and the 80 upper end portion 24' of said shaft is round in cross section and is journaled in the up-standing arm 27 of the casing 28 which encloses the two gears 11 and 13.

An arm 29 journaled on the rounded portion of the vertical shaft a short distance above the upper end of the squared portion is held from moving endwise on the shaft by means of a collar 30 fixedly mounted thereon. The outer end of the arm 29 has 90 a ball and socket connection 31 with the outer end of cranked member 32 which has a hinged connection 33 with the inner end of the horizontal shaft 14 so that as the horizontal shaft is revolved it will reciprocate 95 the vertical shaft and the pounder due to the ball and socket joint and the hinged connection between the two shafts. While the vertical shaft is being reciprocated it will also be rotated by means of the bevel gear 100 connection between the vertical and horizontal shafts. The bevel gears are so proportioned with relation to each other as to cause the vertical shaft to reciprocate a plurality of times with each revolution thereof. 105

In order to provide for the pounder 26 acting equally upon the clothes during its revolution the pounder is formed of oppositely extending segmental portions 34 having outer rounded ends 35 which are of 110 greater width than the medial portion at the hub 26 so that the outer ends will cover a

greater area of clothes than the medial portion thus approximately engaging the clothes equally during its segmental like reciprocations.

5 The width of the segmental portions bear a fixed relation to the number of reciprocations made during each revolution of the pounder so that the pounder will act upon all parts of the clothes. The pounder is constructed with a recess in its lower side to form an air chamber 37 so that when the pounder is pressed downwardly into the water and into engagement with the clothes the water will seal the chamber and the downward pressure of the pounder will force the air and water trapped in the lower portion of the chamber through the clothes and clean the same. The pounder inclines from the end portions upwardly medially and at 15 approximately its highest point is provided with an air inlet opening 38 having a ball valve 39 therebeneath which is held in a valve cage 40. The valve serves to close the opening during the downward movement of the plunger and during the upward movement permits the air to enter the chamber and prevents the pounder from pulling up the clothes.

In the modified form shown in Fig. 6 the 30 crank arm 41 is fixedly connected to the horizontal shaft 14 and is provided with a ball 42 on its cranked end which is adapted to play in the tubular arm 43 journaled on the vertical pounder shaft 24. The outer 35 end of the tubular arm is of angular form to permit the free universal movement of the connection during the operation thereof.

In the form shown in Fig. 7 the cranked arm 41' is provided with a tubular portion 44 and the outer end of the arm 43' is provided with a ball 45 which plays in the tubular portion of the crank arm in substantially the same manner as in the first modification described.

45 From the foregoing description it will be seen that the washing machine is of simple construction and is well adapted for the purpose described.

What I claim as my invention is:

50 1. In a washing machine, the combination of a vertical shaft, a horizontal shaft having a geared connection with the vertical shaft and adapted to continuously rotate the same, a connection between the two shafts for reciprocating the vertical shaft while it is being rotated, and means for rotating the horizontal shaft.

2. In a washing machine, the combination of a support, a gear wheel mounted on said support, a vertical shaft extending slidably through the gear wheel and rotated thereby, a horizontal shaft mounted above the support and having a pinion in mesh with the gear wheel for continuously rotating said vertical shaft, a cranked connection between

the horizontal shaft and the vertical shaft for reciprocating the vertical shaft while it is being rotated, and means for rotating the horizontal shaft.

3. In a washing machine, the combination 70 of a support, a gear wheel mounted on said support and provided with a rectangular bore, a vertical shaft slidably extending through the bore, the portion of the shaft which engages the gear being rectangular in 75 cross section, a horizontal shaft mounted above the support and having a pinion in mesh with the gear wheel for continuously rotating said vertical shaft, a cranked connection between the two shafts for reciprocating the vertical shaft while it is being rotated, and means for rotating the horizontal shaft.

4. In a washing machine, the combination 80 of a support, a gear wheel mounted on the 85 support and provided with a rectangular bore, a vertical shaft slidably extending through the bore, the portion of the shaft which engages the gear wheel being rectangular in cross section, a horizontal shaft 90 mounted above the support and having a pinion in mesh with the gear wheel, a cranked member connected to the inner end of the horizontal shaft, an arm journaled on the vertical shaft and having a universal 95 joint connection with the outer end of the cranked member, and means for rotating the horizontal shaft.

5. In a washing machine, the combination 100 of a support, a gear wheel mounted on the support and provided with a rectangular bore, a vertical shaft slidably extending through the bore, the portion of the shaft which engages the gear being rectangular in cross section, a collar mounted on the 105 shaft above the upper end of the squared portion to form a bearing part, an arm journaled on the bearing part, a horizontal shaft mounted above the support and having a pinion in mesh with the gear wheel, a crank 110 arm having a hinged connection with the inner end of the horizontal shaft and also having a ball and socket connection with the vertical shaft arm to reciprocate the said vertical shaft, a fly wheel mounted on the 115 support and having a connection with the horizontal shaft, and means for rotating the horizontal shaft.

6. A driving mechanism comprising a vertical shaft, a horizontal shaft, a crank pivotally connected to the horizontal shaft, a crank pivotally connected to the vertical shaft, a universal joint connection between said cranks, and means for rotating the horizontal shaft.

7. A driving mechanism comprising a vertical shaft, a horizontal shaft, a crank swingingly connected to one of said shafts, a crank pivotally connected to the other of said shafts, a universal joint connection be-

tween said cranks, and means for rotating the horizontal shaft.

8. A driving mechanism comprising a vertical shaft, a horizontal shaft, a crank pivotally secured to the horizontal shaft, a crank pivotally connected to the vertical shaft, a ball and socket joint connection between said cranks, and means for rotating the horizontal shaft.
10. 9. A driving mechanism comprising a vertical shaft, a horizontal shaft, means for continuously rotating said shafts, means for vertically reciprocating the vertical shaft comprising a crank pivotally connected to the vertical shaft, a crank pivotally con-

nected to the horizontal shaft, and a universal joint connection between said cranks.

10. A driving mechanism comprising a vertical shaft, a horizontal shaft, a crank pivotally connected to one of said shafts, a universal joint connection between said crank and the other of said shafts, and means for rotating the horizontal shaft.

In testimony whereof, I affix my signature, in presence of two witnesses.

JOHN P. DORAN.

Witnesses:

W. S. HENRY,
EDNA L. BOCK.

Copies of this patent may be obtained for five cents each, by addressing the "Commissioner of Patents, Washington, D. C."

It is hereby certified that the name of the patentee in Letters Patent No. 1,156,135, granted October 12, 1915, for an improvement in "Driving Mechanism," was erroneously written and printed as "John P. Doran," whereas said name should have been written and printed *John P. Dorau*; and that the said Letters Patent should be read with this correction therein that the same may conform to the record of the case in the Patent Office.

Signed and sealed this 9th day of November, A. D., 1915.

[SEAL.]

J. T. NEWTON,

Acting Commissioner of Patents.
